ROTARY SELECTIVE SWITCH

Ernest Alfred Bryan, Bexley, England, assignor
to Siemens Brothers & Company Limited, Lon-
don, England, a British company

Application August 6, 1947, Serial No. 766,793
In Great Britain April 5, 1946

Section 1, Public Law 690, August 8, 1946
Patent expires April 5, 1966

3 Claims. (Cl. 179—27.51)

1

This invention relates to rotary selective switch of the kind used for selecting, counting and marking and other purposes in telephone systems.

In switches of this kind it is advantageous to mould the fixed contacts into insulating material and switch banks in which all the fixed contacts are moulded into a mass of insulating material in one operation have been proposed. If all the switches to be manufactured needed the same number of rows of contacts in a bank the production of such a moulded bank would be satisfactory but when switches containing different numbers of rows of contacts are required such proposals are uneconomical, resulting in either the provision of a larger moulding with more contacts than those required or the provision of a number of moulds of different sizes. Besides the wasteful bank that may be produced, corresponding wipers would be required, or at least the wiper shaft would need to be such as to accommodate a variable number of wipers.

Moreover, in the case of a built up bank and assembly of wipers difficulties arise in ensuring the accurate spacing of the several rows of contacts and the co-operating wipers, and the present invention seeks to overcome these difficulties.

According to one feature of the invention a switch bank is built up from a number of moulded units, as many units being assembled together to provide the required number of rows, or levels as they are sometimes called, of contacts. Ideally, a unit would comprise a single row of moulded-in contacts but in practice such a unit would suffer disadvantages owing to its thinness and it is preferable to mould two or even three rows of contacts onto a unit. In order that each unit may be accurately adjusted for thickness so that the spacing between adjacent rows of contacts in assembled units is precisely the same, having regard to manufacturing tolerances, each unit is provided with bosses on at least one of its major surfaces and these bosses may be machined to provide the adjustment necessary. The bosses are preferably situated so that the clamping bolts pass through them.

The unit besides containing the fixed or outlet contacts may include feeder springs for making connection to the wipers to be assembled in con-

2

tact relationship with the moulded-in fixed contacts. In an arcuate bank the feeder springs may be accommodated at one end of the moulded unit, conveniently in a plane between two levels of fixed contacts in the unit. In another arrangement the moulded-in contacts of a level may be of two kinds, a contact of each kind being adapted to be bridged by a multi-armed wiper in any position in the bank. The contacts of one kind may be the so-called fixed contacts and the contacts of the other kind may be feeder contacts and these latter may be formed as strips suitably disposed in the bank.

According to another feature of the invention 15 the wipers are assembled as units, there being as many wipers in a unit as there are rows of contacts in a bank unit with a spacing corresponding to that of the contact rows. Each unit is provided with surfaces whereby the overall 20 axial length may be adjusted. The wipers forming a unit may be assembled on a metal tube and are spaced apart to correspond with the spacing of the contact rows of a bank unit and insulated from one another and from the tube, 25 a number of units being clamped together to form a complete wiper assembly which is mounted on the wiper shaft. By this means the individual wipers may be adjusted for pressure and alignment before assembly on the shaft a final setting being given on fitting the wiper shaft to the switch bank.

The wiper assembly and the driving mechanism may be separately assembled so that the wiper shaft may be removed without its being 30 attached to the relatively heavy driving mechanism.

An arcuate contact bank and wiper assembly embodying the invention is illustrated by way of example in the accompanying drawings. In the drawings Fig. 1 shows a plan view of a bank unit and Fig. 2 a front elevation of the unit. Fig. 3 is a view showing a number of units spaced along the clamping bolts before being brought into contact and clamped together. Fig. 4 is a plan view of a four-armed wiper, a sectional view being shown in Fig. 5; and Fig. 6 is a view of a wiper assembly corresponding to the view of the bank units shown in Fig. 3.

50 The bank units and their assembly will first

be described with reference to Figs. 1, 2 and 3. The bank unit illustrated consists of two levels of contacts 2 moulded into a block 1 of synthetic resin or other suitable thermo-setting plastic substance. In some cases it may be convenient to mould more than two levels into a unit. The block 1 has bosses 3 formed on its two major surfaces, three such bosses on each surface are shown, and these may be machined, if necessary, to determine the exact overall thickness of the unit. The bosses and the portion of the block lying beneath them have holes through them to accommodate the clamping bolts 6. In the unit illustrated a level consists of a number of fixed contacts 2 and at each end of the level a strip 4 serving as feeder contacts. The arcuate length of the strips 4 will be equal to that of half the number of contacts 2 so that a pair of electrically connected wiper arms will make contact, one with a feeder strip 4 and the other with a fixed contact 2 in any position in the bank. The tag ends of the contacts and strips to which the connecting wires are soldered are designated 5. The several units are assembled on clamping bolts 6 which pass through the bosses 3 and the assembled units are brought into contact with one another through the bosses and clamped between end plates 7 by means of nuts 8 on the bolts 6. A bank built up by this means may consist of a number of like units or units comprising different numbers of levels, according to the number of levels required in the switch. A greater measure of standardisation may be had by forming all units alike which leads to simplification in determining the overall dimensions of the individual units and requires only one size of mould.

Reference will now be had to Figs. 4, 5 and 6 which show a wiper unit and the manner of assembly. The wiper unit shown is adapted to be used with two-level bank units having co-planar fixed contacts and feeder strips as illustrated in Fig. 1 and comprises two four-armed wipers of the kind shown in plan in Fig. 4. A wiper consists of a central part 9 in which is a central hole for mounting them on a carrier, with four arms 10 at right angles to one another, the arms turning from the central part through a right angle at the elbow 11 leaving a slot 12 between the arm and the central part. The slot 12 and the shape and position of the hole 13 assist in giving the arm the desired flexibility. Each arm has attached to it by eyelets 14 a tip member 15 the tip of which is suitably shaped for rubbing on the band contacts. There are actually two tip members 15 secured one on each side of the end of the arm and the tips of these members are adapted to rub one on each side of the contacts of a level. Two wipers with insulating washers 16 on each side of them at their centre are spaced apart by member 17, the spacing corresponding to the spacing of two levels in a bank unit, the wipers and spacing member being passed over an insulating tube 18 and assembled on a metal carrier tube 19. Further members 20 are positioned on the outside of the insulated wipers, over the insulating washers 16 and surrounding the tubes 18 and 19, the member 20 being formed with recesses to accommodate the tube 18 and the ends being recessed to accommodate the metal of the tube 19 that will be spun over in completing the assembly. The overall axial length of the unit may be adjusted, if necessary, by machining the surfaces or by a suitable compressing operation of the two members 20,

so that the distance between opposite faces of the members will correspond with the thickness of a bank unit over the bosses 3.

The wipers 9 and their tip members 15 may be of different materials and of different thicknesses whereby a stiff centre part and more resilient tips may be had. In fitting the tip members to the wiper arms they are first tack welded to position them after which the eyelet holes are punched and the eyelets inserted and riveted over. The alignment and pressures of the tip members may be adjusted apart from the complete assembly on the wiper spindle. In assembling the wipers as a unit, they and the spacing and other insulating members are assembled on the carrier tube 19 and while the unit is held under pressure the ends of the tube are spun over to enter the recesses in the member 20, the metal of the tube lying below the surface of the members 20. The required number of units are assembled on the wiper spindle 21, the assembly being shown loose in Fig. 6, and after the units have been brought into contact with one another nuts are threaded on the threaded end or ends of the spindle to clamp all the units together. The clamping nuts bear on the members 20 and not on the carrier tubes 19, the ends of which, as before mentioned lie below the surfaces of the members 20. After assembly on the spindle and the insertion of the spindle in position relative to the contact bank any final adjustment of the tips to agree with the bank contacts is readily made by slightly setting the elbows 11 up or down.

I claim:

1. For use in a selecting switch, a wiper assembly consisting of a plurality of wipers mounted in spaced relation, a plurality of arcuate moulded contact units, each unit having a series of contacts for cooperation with one of said wipers, integral spacing bosses on at least one of the surfaces of each of said units, and shaft means for clamping said units together in such a manner that the spacing between adjacent units and therefore the alignment of said contacts with said wipers is determined by the size of the bosses on said units.

2. For use in a selecting switch, a plurality of arcuate moulded contact units, each of said units having a series of contacts, a wiper assembly comprising a shaft and a plurality of wiper assembly units mounted on said shaft and spaced for cooperative relationship with said series of contacts, each one of said wiper assembly units comprising wipers mounted between tubular insulators having circular recesses in the ends thereof, and a metal tube projecting axially through said wipers and said tubular insulators, said metal tube having its ends spun into said recesses of said tubular insulators so that said metal tube does not project from said tubular insulators thereby causing no interference with the spacing between said wiper assembly units and therefore the cooperation thereof with said series of contacts.

3. For use in a selecting switch having a plurality of wiper assembly units mounted adjacently on a shaft, a wiper assembly unit comprising a plurality of wipers mounted between a plurality of annular insulators, the first and last insulator having circular recesses in the ends thereof, and a metal tube projecting axially through said wipers and said insulators and having its ends spun into said recesses of said insulators thereby rigidly maintaining said assembly unit together without projecting beyond the ends of said first and last insulators, the ends of said insulators

therefore being free to act as the adjacent surface for other wiper assembly units.
